UNITED STATES PATENT OFFICE

2,670,032

OIL GAS GENERATOR-BURNER

Leonard Vignere, Sr., Salem, Ohio

Application October 4, 1950, Serial No. 188,380

4 Claims. (Cl. 158—4)

1

This invention relates to the construction of an oil gas generating retort and burner, adapted for use either in domestic or industrial installations, whether they be original installations or conversions from other types of previously installed burners. More particularly the invention relates to oil burners of the gun type, as distinguished from those falling into that grouping commonly designated as pot type oil burners.

For proper appreciation of the main objects of the present invention, it is worth repeating the well known fact that oil is in the final analysis a gas, changed to a liquid state. An important object of the present invention is to provide a burner structure or retort wherein the liquid is first broken down to its original gaseous state by heating it almost to the flash point and supplying the requisite amount of air to support perfect combustion.

I propose to produce this highly desirable result by the provision of an oil gas-generating burner including a retort, so formed as to cause an initial mixture of oil spray and air to be ignited by an electrode or its equivalent, the resultant flame heating a centrally disposed portion of an overlying retort in a manner to provide a "hot spot" which thereafter preheats the oil spray impinging thereagainst so as to form a gas. The flame, meanwhile, travels out to the outer circumference of the retort, there heating and keeping hot a plurality of deflecting ribs which in turn keep hot the entire retort. After said initial ignition of the mixture, there is no flame at the "hot spot" area, but this area remains sufficiently heated to form any oil spray or mist coming in contact with it into a gas that is deflected outwardly and radially of the gasifying area and is ignited at the periphery of the retort. The result is a highly desirable blue flame not unlike that caused by combustion of natural gas, which flame is directed outwardly from the deflecting ribs in a horizontal swirling motion.

Cooperating with the retort above mentioned is a vertically disposed gun-type burner structure as distinguished from horizontally disposed gun-type burner structures.

Horizontally disposed gun-type burners are generally extended through a side wall of the furnace or boiler into the ash pit thereof. Burners of this type do not lend themselves to economical use, and this is because the ash pit usually must be lined with fire brick or other refractory material to sustain combustion, the ash pit in this way being formed into a combus-

2

tion chamber for the burner. A burner of this type is in point of actual fact no more than a sprayer, since it sprays the liquid fuel directly against a refractory wall, where the combustion takes place, dependence being had upon the refractory material to sustain smokeless and sootless combustion.

By reason of their very nature, such gun type burners would generally be installed horizontally, because of the tendency of the sprayed fuel to trickle back to the spray tip or fall downwardly thereupon whenever the spray becomes too heavy for combustion at a location remote from the tip. The result is carbonizing of the spray tip or nozzle, with obvious reduction or loss of function thereof.

Pot type burners, on the other hand, are generally installed vertically, and have notable deficiency in that there is considerable residue after combustion, including a hard carbon deposit.

An important object also is to provide a vertically disposed gun-type oil burner, and a combustion head or retort therefor, wherein the combustion will result in the provision of a flower-like flame, as distinguished from the flame produced by the horizontal gun type burner, and wherein said flame will impinge not upon a refractory material, as is now generally the case, but rather, against the heating walls of the furnace or boiler in which the unit is installed.

Another important object is to provide an oil burner and combustion head or retort construction so formed as to produce the end result of complete combustion, without residue or carbon deposits, by successively breaking the fuel into small particles, intermixing these thoroughly with air to support combustion, and then disintegrating the mixture into a highly combustible gaseous fog by impingement of the mixture against heated component parts of the combustion head or chamber prior to complete combustion.

With the foregoing and other objects in view which will appear as the description proceeds, the invention consists of certain novel details of construction and combinations of parts, herein-after more fully described and pointed out in the claims, it being understood that changes may be made in the construction and arrangement of parts without departing from the spirit of the invention as claimed.

Referring to the drawing:

Figure 1 is a vertical sectional view through a vertically disposed gun type oil burner and combustion head or chamber formed in accordance

with the invention and through a furnace in which the structure is mounted.

Figure 2 is a top plan view of the oil burner, the combustion head being removed and a portion of an air nozzle forming part of said burner being broken away.

Figure 3 is a fragmentary perspective view of an outer ring of the wick.

Figure 4 is a vertical section view through the combustion head or chamber alone.

Figure 5 is a bottom plan view of said head.

Figure 6 is a horizontal section through the head taken on the line 6—6 of Figure 4.

Figure 7 is a view similar to Figure 1 in which is illustrated a modified form of retort or head of a two piece formation used in cooperation with a burner formed as in Figure 1.

Figure 8 is a bottom plan view of the lower portion of said modified retort.

Figure 9 is a section through the upper portion of said modified retort taken on line 9—9 of Figure 7.

Referring to the drawings in detail, the oil burner and combustion or burner head constituting the present invention have been illustrated as mounted in a conventional domestic type furnace having the outer wall 1 mounted upon the floor or other supporting surface 2. The furnace includes the bowl-shaped fire box 3 disposed above and in communication with the ash pit 4, these being illustrated somewhat diagrammatically, as one form of furnace or boiler construction among many others for which the present invention is well suited.

Formed in the wall 1 is an opening 5 through which extends a draft tube or air conduit 6 leading from a blower 7 driven by a motor 8 mounted on one side wall of the blower housing. A pump 9 is mounted on the opposite side wall of the blower housing and is also driven from the motor 8 for the purpose of forcing fuel through the pressure line 10 leading to the fuel atomizing nozzle.

All this is more or less conventional construction, and it may be noted that in a horizontal gun type burner, the fuel nozzle is usually disposed in the inner end of the conduit 6, and discharges its spray horizontally into the ash pit 4.

In accordance with the present invention, however, an L-shaped extension conduit 12 having a ninety degree bend intermediate its ends is mounted upon the inner end of the conduit 6. In the present instance, the conduit 12 has at its lower end the bell 13 receiving the inner terminus of the conduit 6, ears 14 being formed integral with said bell and projecting laterally from opposite sides thereof. Threaded openings are formed in the ears, and bolts 15 extend through said openings to provide adjustable supporting legs. At the bend of the conduit 12 is formed a bracket 16 also provided with ears having threaded openings for the bolts 17 constituting supporting legs adjustable with and cooperating with the bolts 15 to support the conduit 12 and associated parts at a desired elevation.

The upper end of the conduit 12 extends vertically into the lower end of the fire box 3, the wall of the fire box comprising one of the heating walls against which maximum heat should be directed for optimum heating efficiency of the installation. Said upper end of the conduit is flared as at 18 and formed with the outturned annular flange 19 grooved as at 20 to provide an annular seat for a depending peripheral flange

21 of a circular base plate 22 of an air nozzle supported upon the conduit 12.

The base plate 22 is horizontally positioned so as to extend transversely across the outlet end of the vertical conduit 12.

The air nozzle also includes a frusto-conical centrally apertured cover plate or ring 23 overlying and spaced above the marginal part of the base plate. In the present instance the cover plate is made integral with the base plate. However, it is not critical to the invention that it be so made, or even fixedly connected to the base plate, it being mainly important that the cover plate or ring overlie protectively the marginal portion of the base plate while yet leaving the central area of the air nozzle open to provide an aperture for sprayed fuel and the air that is to be intermixed therewith. In this connection, some of the sprayed fuel may tend to trickle back downwardly within the air nozzle, and accordingly, I form in the cover ring, where it intersects with the periphery of the base plate, a circumferential series of weep holes 24.

The protectively covered marginal portion of the base plate is formed with concentric rows of air outlet openings, two such rows being illustrated in the present instance, though more or less can be provided as desired, so long as all the openings underlie the covering. In each of these openings is mounted an upstanding nipple or sleeve 25 defining passages for the air flowing out of the conduit 12, and these nipples extend a short distance above the top surface of the base plate 22 to prevent such fuel as is to drain through the weep holes from draining through the air outlets.

As before noted, the covering ring at its upper end is formed with a large central aperture 26 through which the air and sprayed fuel passes, and below the aperture a fuel spray nozzle 27 is mounted vertically, to discharge upwardly through the aperture. The nozzle 27 is of the hollow cone type well known in the art, and is exteriorly threaded for threaded engagement in selected positions of vertical adjustment relative to the edge of the aperture 26, in a threaded center opening formed in the otherwise imperforate center portion of the base plate 22. Lock nuts 28 are threaded on the nozzle against the top and bottom surfaces of the base plate to hold the nozzle in said selected positions of adjustment and also prevent leakage between the nozzle 27 and the opening of the base plate in which it is mounted.

To ignite the combustible fuel-air mixture any of various well known means can be used, such as a pilot light or electrode igniter, and except as necessarily required by the scope of the appended claims, I do not desire to limit myself to any particular igniting means. In the present instance, as one example of a suitable igniting means, I provide cables 29 mounted at 30 upon the conduit 12 and extending upwardly therefrom through exteriorly threaded sleeves 31 to the igniting electrodes 32, the spaced tips of which are disposed above the cover ring 23. The sleeves 31 are mounted in threaded openings 33 formed in a horizontally disposed annular support plate 34 that surrounds the air nozzle and is supported upon the flange 12. Lock nuts 35 secure the sleeves in selected positions of adjustment and also prevent leakage of fuel flowing over the support plate.

The peripheral area of the support plate is formed with a circumferential depression 36 di-

vided into concentric annular seats through the provision of an upstanding partition 37 cast integral with the support plate. The inner seat or trough defined by said partition is a repository into which said backwardly trickling fuel draining through the weep holes and flowing across the support plate 34 is ultimately deposited.

It is desirable, in this connection, to provide for the combustion of fuel so deposited and to this end, there are positioned in the inner trough a pair of spaced upstanding rings 38 and 39 defining means for supporting a quantity of absorbent non-combustible material 40 such as asbestos. The fuel moving into the inner trough tends to saturate the material 40 and is burned off as it intermixes with air provided for by the formation, in said inner and outer rings 38 and 39, of perforations 41 and 42 extending through the full area thereof.

In the outer seat or trough of the support plate is positioned an upstanding ring 43 constituting the inner wall of an outer channel the bottom of which is formed by a flat ring 44 and the outer wall of which engages the wall of the fire box 3 of the furnace. This channel is filled with asbestos or other non-combustible material 45.

With an oil burner constructed as described above, I utilize in the form of Figure 1 a burner or combustion head or retort generally designated 46 and comprising a rigid assembly supported by the plate 34 in an elevated position above the burner. The head 46 includes a circular series of radial vertically disposed legs 47 that seat upon the plate 34 and extend upwardly therefrom. At their upper ends, the legs 47 are integral with wide radial partitions or ribs 48 constituting extensions of the legs. In the present instance six equidistant legs and partitions are provided but more or less can be used to good advantage.

A deflecting cone 49 is supported by and rigidly attached to the curved top edges of the partitions 48. The cone is integral with a horizontally disposed peripheral flange 50, the cone and flange together defining a circular top deflector on the burner head deflecting the flame radially and outwardly to impart to it a flower-like form. A lower baffle ring 51 of annular upwardly inclined configuration is spaced from and underlies the top deflector and is concentric therewith. The baffle ring 51 is rigidly secured to the lower portions of the wide radial partitions 48.

Completing the formation of the burner head are vertical baffles 52, 53 extending between the baffle ring 51 and the deflector 50, these being inclined out of radial alignment with the dividing partitions so as to impart to the flower-like flame a swirling lateral motion, thereby to direct the full effect of the flame laterally against the surface of the wall 3 to be heated. The baffles 53 constitute extensions of the dividing partitions while the baffles 52 are individual plates rigidly secured to the marginal portion of the deflector 50.

In use of the burner, on a call for heat by the usual room thermostat, not shown, or equivalent means, a circuit is closed through the electrodes 32 and motor 2 in the usual manner. Air is thus forced at substantial velocity through the draft tube or conduit 12 by the blower, simultaneously with the pumping of liquid fuel through the pressure line 10 and spraying of said fuel from the spray nozzle 27. The hollow cone formation of the sprayed fuel is illustrated in dotted lines in Figure 1, and it is seen that the cone is directed upwardly and outwardly, slanting across

the path of the air forced under pressure upwardly through the aperture 26 at the upper end of the air nozzle. A thorough mixture of the sprayed fuel and air is obtained in this manner, and this is ignited at the periphery of the air nozzle and is deflected radially in all directions by the burner head. Rapid heating up of the material of which the burner head is made now takes place, and as combustion continues, the heat of the burner head tends to disintegrate the intermixed fuel and air at the center area of the burner head before full combustion thereof in the marginal area of the head. Thus, the desirable result is obtained of generating the intermixed fuel and air into a fixed gas with the soot or carbon in suspension for thorough combustion by the heat of combustion.

Of major importance is the fact that the structure provides what has heretofore not existed in gun-type oil burners of the general type in widespread use today, namely, a vertically disposed gun type burner characterized by its specific adaptability for producing an unusually desirable shape of flame at a particularly favorable location within the furnace. In this connection, adaptation of the burner for vertical mounting is possible mainly because of the means provided for disposition of such liquid fuel as may be too heavy for continued upward and outward movement with the air to be intermixed therewith to support combustion. Such fuel, if it drops back through the aperture 26, will drop to the imperforate center portion of the base plate 22 and passing between but not through the nipples 25, will drain off through the weep holes 24, moving thereafter across the plate 34 and into the trough at the margin of the plate. The fuel is then absorbed by the asbestos 40 and is continuously consumed.

If the fuel drops down upon the protective cover ring 23, it gravitates directly to the plate 34, and then into the trough as above noted. The protective cover ring, of course, makes it impossible for the falling fuel to drop into the air outlets of the draft tube.

Considering now the modified construction illustrated in Figures 7 to 9 inclusive, there is there illustrated a retort of two-piece formation the overall shape or configuration of which is particularly adapted to preheat the sprayed fuel mixture impinging thereagainst and generate a gas therefrom, while effecting a suction of the mixture to the periphery of the retort for full combustion at said periphery.

The modified retort is supported upon and overlies a burner formed as hereinbefore described and includes a lower portion that has a plurality of radially disposed vertically extending legs 54. These rest upon the plate 34, and at their upper ends are integral or otherwise rigid with an inverted frusto-conical baffle ring 55. The ring 55 is integral at its inner periphery with an annular flange 56 that extends above and below said inner periphery of the baffle ring, to complete the formation of the lower portion of the modified retort.

Supported upon the lower portion but wholly free of connections thereto is the upper portion of the retort, this being formed with a plurality of radial circumferentially spaced vertical partitions 57. The bottom edges of the partitions simply rest upon the baffle ring and are of inclined formation so as to complement the inclination of the ring.

The outer edge portions of the partitions 57

are vertically disposed deflecting members or baffles that are inclined out of radial alignment with the main body portions of the partitions as readily seen from Figure 9. Spaced peripherally of the retort are other vertically disposed radially offset deflecting ribs 58, the members 58 and 59 serving to deflect the gases at the time of combustion laterally and outwardly from the report in a swirling motion in the same manner as hereinbefore described with reference to the first form of retort.

At their upper ends, the partitions 57 and deflecting ribs 59 are integral or otherwise rigid with the top plate 60 of the upper retort portion, this being of circular configuration and having a centrally disposed deflecting cone 61. The cone 61 is hollow, made so by the provision of a deep center recess 62 in the top plate.

It may be noted that the provision of a two-piece retort facilitates assembly within the furnace, since an installer is enabled to position the lower retort portion as a first step, after which the upper retort portion is simply placed thereupon without the necessity of effecting special connections between the parts, with both pieces being capable of entry separately through furnace openings of limited size.

Considering the operation of the modified retort construction, it is understood that the liquid fuel is sprayed upwardly from the nozzle 27 in the same manner as in the first form of the invention. Initially the resultant fuel-air mixture is ignited by the electrodes in the space immediately below the cone 61. This flame heats the "hot spot" constituted by the hollow cone and when the cone temperature rises sufficiently, the oil spray striking it is vaporized, forming a gas. At the same time, the flame travels to the outer circumference of the retort, there being no flame below and immediately surrounding the hot cone after the initial ignition.

At the outer circumference of the retort, the deflecting ribs 58, 59 are kept heated by the flame burning at said outer circumference. This in turn serves to keep the entire top plate 60 hot enough to vaporize an oil spray or mist coming in contact therewith.

The result, I have found, is a blue flame of excellent quality which is discharged at high velocity through the openings defined between the several ribs 58 and 59, in a horizontal swirling motion.

With further reference to the operation of the retort in bringing these highly desirable results about, it should be noted that the addition of the flange 56 provides an area through which the oil-air mixture is sprayed upwardly at high velocity and this in turn causes a suction in the area immediately below said flange 56 and surrounding the member 23. The suction created causes hot gases from the area at the outer circumference to be drawn under the baffle ring 55 into said oil-air mixture as the mixture is sprayed

upwardly through the flange 56, thus aiding in preheating of the mixture.

Also of importance is the fact that the ring 55 constitutes a vaporizing plate which, due to its heated condition, assists in vaporizing of any part of the fuel-air mixture that may drip downwardly thereupon if not fully gasified within the gasifying area disposed immediately above said vaporizing plate or ring 55.

I claim:

1. An oil burner comprising an upwardly extended draft tube, an air nozzle mounted upon the upper end of said tube and including a substantially horizontal base plate having openings formed in its marginal area, nipples mounted in said openings and projecting above the surface of the base plate, and a frusto-conical cover ring mounted upon said base plate, there being a large center opening formed in said cover ring at its upper end and a circumferential series of weep holes at its lower end, the cover ring constituting means protectively shielding said base plate openings against gravitating fuel particles, the walls of said weep holes constituting means for leading off fuel flowing over the base plate surface and between the nipples, a liquid fuel spray nozzle mounted in the center portion of the base plate and extending upwardly toward the center of the cover ring to spray fuel therethrough for intermixing with air channeled from the base plate openings to said center opening, and a drain plate having a depression and surrounding said air nozzle for receiving fuel draining through the weep holes.

2. An oil burner as in claim 1, and said burner including a plurality of foraminous rings supported in the depression of said drain plate, and a quantity of non-combustible, fuel absorbing material held between said foraminous rings.

3. An oil burner as in claim 1, and said burner including substantially non-combustible, fuel-absorbing material; and means retaining said material in the depression of said drain plate.

4. An oil burner as in claim 1, and said burner including a plurality of upwardly-extending foraminous rings supported in the depression of said drain plate, and asbestos held between said foraminous rings.

LEONARD VIGNERE, SR.
